UNITED STATES PATENT OFFICE

HERBERT E. WHITE, OF YOUNGSTOWN, OHIO, ASSIGNOR TO TRUSCON STEEL COMPANY,
OF YOUNGSTOWN, OHIO, A CORPORATION OF MICHIGAN

METALLIC DECK STRUCTURE

Application filed October 26, 1928. Serial No. 315,311.

One of the objects of the present invention is to provide a metallic roof deck or similar structure that can be quickly and conveniently assembled and fastened in place without the necessity of the workmen operating beneath the deck. A further and important object is to provide novel fastening means that will effectively hold the parts in place and can be utilized in connection with ordinary commercial structural members. A still further object is to provide novel means for producing a joint between abutting ends of the deck members or sections.

In the accompanying drawings:

15 Figure 1 is a plan view of a portion of a roof deck constructed in accordance with the present invention.

Figure 2 is a cross sectional view of the same.

20 Figure 3 is a sectional view on the line 3—3 of Figure 1.

Figure 4 is a sectional view on the line 4—4 of Figure 3.

Figure 5 is a plan view of the joint piece.

25 Figure 6 is a detail perspective view of one of the fastening clips.

Figure 7 is a view in elevation of a yoke of said clip.

Figure 8 is an edge view of such yoke.

30 In the embodiment disclosed, supporting members or purlins are employed that may be channel beams. One of these is shown at 9. The same is located on edge to provide a horizontally disposed flange 10, which flange

35 as is well known, normally tapers from the web to its free edge. This tapered formation is made use of as hereinafter explained.

Supported on the purlins 9 and extending transversely thereof is a deck formed of 40 sheet metal strips or members designated generally by the reference numeral 11. These members, each comprises a body or top wall 12 with side walls 13 and 14 formed by flanging the margins of the metal. One 45 of the side walls, as 13, is provided with an outstanding terminal rib or flange 15. The other side wall 14 is also provided with a terminal outstanding flange 16 preferably wider than the flange 15, and joined to the 50 side wall by an inwardly extending bead 17.

This bead produces a groove 18 at the bottom of the side wall 14 and above the flange 16 (see Fig. 6). In laying the structure, the members 11 are located side by side, as shown in Figure 2, with the flange 15 of one member fitting into the recess or groove 18 of the next adjacent.

These members are held in place by the following clip structures. At each purlin 9 a clip plate 19 is placed on the flange 10 thereof, so that it lies on said flange 10 and overlies the flange 16. To position it, said plate is preferably provided with a down-turned portion 20, the ends of which terminate short of the ends of the plate 19, forming abutment stops 21. The plate is thus reversible and can be employed irrespective of the direction in which the flange 10 of the purlin extends. The plate 19 is gripped to the purlin 9 by a yoke element 70 22 that embraces the flange 10 and plate 19, and is preferably provided with inturned spurs 23. This yoke may have a driving head 24. The distance between the free ends of the spurs 23 is preferably such that 75 the spurs will fit upon the free margin of the flange 10, but as this flange increases in width toward the web 9, it will be evident that the yoke must be driven into place, so that the spurs 23 will bite into the underside 80 of the flange 10 and the upper side of the plate 19, thus effectively holding all the parts in place.

In laying the members 11, it will be noted that when one is placed in position, the flange 16 thereof is exposed and that consequently the workman may stand or kneel upon this section, place the plates 19 over the exposed flange 16, and drive the yokes "home". He thus does not have to work or operate beneath the member. When he has fastened the same down, the next member is placed over the fasteners by inserting the flange 15 into the groove 18. This brings the flange 16 thereof in exposed position to be fastened and the operation is of course repeated until the deck is laid. It will be observed in this connection that the end of the plate 19 terminates short of the side wall 14, so as to permit the introduction of 100

the flange 15 into the groove 18. While the strips or members 11 may be formed of relatively great length, it becomes necessary at times to use two or more in one row—
 5 that is, end to end, and a novel joint is provided for this purpose, as illustrated in Figures 1, 3 and 4. The ends of the adjacent members 11 are slightly separated and a channeled joint piece 25 has its ends fitted
 10 into the adjacent ends of said members 11 and bridges the space between them. This joint piece is preferably formed of sheet metal bent to channel form, with its end portions preferably inset as shown at 26 to
 15 permit its ready insertion. The downturned ends 27 of the joint piece rest respectively on the bead 17 and flanges 16. The central portion of the joint piece is provided with a transverse rib 27^a that fills the space be-
 20 tween the ends of the adjacent sections 11 and is in substantial alinement therewith.

Where the end of the deck abuts a wall or other obstruction, the space between one member 11 and the wall may be less than
 25 the width of the members, in which case the structure shown in Figures 1 and 2 may be employed. The wall herein is indicated at 28. Abutting the wall is a section of one member, as illustrated at 29. It is pro-
 30 vided with the side wall 14, the flange 16 and bead 17. In other words, it may be an ordinary member cut longitudinally and of course can be cut diagonally if the wall is diagonal to the direction of the deck mem-
 35 bers 11. In the space between the wall 14 and the first standard member 11 is a bridge piece, comprising a top wall 30 having a depending wall 31 provided with a flange 32 fitting in the socket or groove of the
 40 bead 17. The top wall 30 may overlie the adjacent standard member 11 and be secured thereto by screws 33 or other fasteners. This, however, would ordinarily provide a single supporting wall 13 that would make
 45 a weak point in the deck structure. In order to overcome this difficulty, a reenforcing wall 34 may be employed corresponding in all respects to the wall 14 with its flange 16 and bead 17 of a standard member. This
 50 is fitted into place and held by clips corresponding to those already described.

As already shown this deck structure can be laid without the workmen either lying over the top and working underneath or
 55 working upwardly from beneath because the fasteners when placed are exposed and readily available from the tops of the deck already laid. Further than this, a smooth deck or floor is provided on which heat insulating material and a roof body can be placed.
 60 The structure is very strong since it is supported by a double side wall at each point and this it will be noted is true even where an obstructing wall or termina-
 65 tion requires a special arrangement. The

joints between the adjacent ends of the members moreover are as strong or stronger than the remaining structure and can be readily assembled.

From the foregoing, it is thought that the 70 construction, operation and many advantages of the herein described invention will be apparent to those skilled in the art, without further description and it will be understood that various changes in the size, shape, 75 proportion and minor details of construction may be resorted to without departing from the spirit or sacrificing any of the advantages of the invention.

What I claim is:

1. A deck structure of the character set forth, comprising flanged supporting beams, metallic deck strips having lips resting thereon, clip plates that overlie the beam and lips, and retaining yokes embracing the 85 plates and the flanges of the supporting beams.

2. A deck structure of the character set forth, comprising flanged supporting beams, metallic deck strips having lips that rest 90 thereon, clip plates that overlie the beam and lips, and retaining yokes embracing the plates and the flanges of the supporting beams, and having inset spurs that bite the 95 strips and flanges.

3. A deck structure of the character set forth, comprising flanged supporting beams, a plurality of deck members located across the supporting beams and having coacting side walls that detachably interfit, certain of 100 said side walls having flanges that lie transversely of and upon the beam and outstand on the outer sides of the wall so that they are exposed when laid and are covered by the next adjacent member, and clips that 105 embrace the flanges of the beams and members and are applicable thereto when exposed and prior to the addition of the adjoining member.

4. A deck structure of the character set forth, comprising flanged supporting beams, a plurality of deck members located across the supporting beams and having coacting side walls that detachably interfit, certain of 110 said side walls having outstanding flanges that lie transversely of and upon the beam and are covered by the next adjacent member, clip plates that lie on the beams and overlap the flanges of the members, and yokes that embrace the beam flanges and 115 plates and serve to secure the plates to the beams and clamp the members to the beams.

5. A deck structure of the character set forth, comprising supports and channel strips secured side by side to the supports and having side walls that are interfitted, each member having an outstanding flange 120 that underlies one side of the channel of the adjacent member and also having an underlying bead, certain of said members being 125

located end to end, and a channeled joint piece having its ends fitted into the channels of said latter members and with its side walls supported by the said flanges and 5 bead.

6. A deck structure of the character set forth, comprising supports and channel strips secured side by side to the supports and having side walls that are interfitted, 10 each member having an outstanding flange that underlies one side of the channel of the adjacent member and also having underlying beads, certain of said members being located end to end, and a channeled 15 joint piece having its ends fitted into the channels of said latter member and with its side walls supported by said flanges and beads, the intermediate portion of the joint piece being provided with a transverse outstanding rib that is located between the 20 ends of the said latter members.

7. A deck structure of the character set forth, comprising supports, channelled deck members having their flanges on the supports, an abutment wall, a reinforcing flange member along the side of the deck member that is adjacent to the abutment wall, and a filling deck member separate from the reinforcing member and having a supporting 30 flange adjacent the abutment wall, said filling member having a top wall overlying the reinforcing flange member, and supported thereby.

8. A deck structure of the character set 35 forth, comprising flanged carrying beams, metallic deck strips laid across the beams and having outstanding flanges, clip plates that lie on the beams and extend over the flanges of the deck strips, and separate retaining yokes extending over the portions 40 of the clip plates that lie on the beam flanges and extending under the flanges to grip the clip plates and clamp them on the beam flanges.

45 9. A deck structure of the character set forth, comprising flanged carrying beams, metallic deck strips laid across the beams and having outstanding flanges, clip plates that lie on the beams and extend over the 50 flanges of the deck strips, said clip plates having downturned stop portions that abut the edges of the beam flanges, and separate retaining yokes extending over the portions of the clip plates that lie on the beam flanges 55 and extending under the flanges to grip the clip plates and clamp them on the beam flanges.

10. A deck structure of the character set forth, comprising flanged carrying beams, 60 metallic deck strips laid across the beams and having outstanding flanges, clip plates that lie on the beams and extend over the flanges of the deck strips, said clip plates having downturned stop portions that abut 65 the edges of the beam flanges and stop short

of the portions of the plates that overlie the beam flanges, and separate retaining yokes extending over the portions of the clip plates that lie on the beam flanges and extending under the flanges to grip the clip 70 plates and clamp them on the beam flanges.

In testimony whereof I affix my signature.
HERBERT E. WHITE.
